UNITED STATES PATENT OFFICE.

CHARLES C. BATTEY, OF SPRINGFIELD, MASSACHUSETTS.

EXCAVATING-MACHINE.

SPECIFICATION forming part of Letters Patent No. 766,584, dated August 2, 1904.

Application filed July 31, 1903. Serial No. 167,742. (No model.)

To all whom it may concern:

Be it known that I, CHARLES C. BATTEY, a citizen of the United States of America, and a resident of Springfield, in the county of Hampden and State of Massachusetts, have invented certain new and useful Improvements in Excavating-Machines, of which the following is a full, clear, and exact description.

This invention relates to improvements in excavating-machines especially available for digging dirt, sand, &c., from any place and delivering the same from its successively-traveling shovels or buckets into a cart or other receptacle, and the machine is also well adapted for excavating for cellars and for digging trenches.

The invention consists in the combinations and arrangements of parts, all substantially as hereinafter fully described, and set forth in the claims.

The improved excavating-machine is illustrated in the accompanying drawings, in which—

Figure 1 is substantially an elevation, some of the parts appearing in vertical section. Fig. 2 is a plan view of the machine. The section-line on Fig. 2 indicates the plane on which the parts in section in Fig. 1 are drawn. Fig. 3 is a perspective view of one of the shovel-buckets. Fig. 4 is a perspective view of an appliance carried in advance of the shovel-bucket for loosening the dirt or sand.

Similar characters of reference indicate corresponding parts in all of the views.

The excavating-machine is portable, being mounted on a truck A, and on said truck is a platform C, centrally swiveled, as indicated at *a*, whereby such platform may have its position along the main platform of the truck, as shown in full lines in Fig. 2, or its position transversely thereof, as indicated by the dotted lines in said Fig. 2. At the end portion of the said platform C is an upright frame B, which serves as a support for various of the parts of the excavating apparatus.

The excavating apparatus comprises a duplicated sprocket-chain D, the same running around a sprocket-wheel *b*, mounted on a shaft *d*, which is journaled in suitable bearings at an upper part of the said frame B. Said

sprocket-wheel is driven from the motive power furnished by the engine or motor E on the truck-platform C, said engine having on its shaft a sprocket-wheel *f*, on which runs a sprocket-chain *g*, which also runs around a sprocket-wheel *g*² on the shaft *d*, on which the aforementioned sprocket-wheel *b* is affixed.

F and G are duplicated booms pivotally connected at *j* and *k* at opposite sides of the platform C and carrying at their extremities duplicated guiding-sheaves *h* and *I*, around which run the said sprocket-chains, said sprocket-chains carrying the shovel-buckets J, suitably distanced one from another, and also the harrowing appliances K.

The boom F in use is extended with downward inclination to insure that the chain-carried shovel-buckets will descend properly low to take earth or sand, while the boom G is upwardly inclined, so that the buckets guided around the end sheave thereof will be carried properly above the ground preparatory to dumping, and in addition to the booms F and G, carrying the duplicated sheaves, as mentioned, there is an intermediate duplicated bar or boom L, extended from one edge of the truck beneath the latter on a downward inclination and carrying sprocket-chain-guiding sheaves *l* for holding the chains against undue slackening in their inclination in an upward direction from contact with the depressed sheaves *h* and the higher sheaves *i* at opposite sides of the apparatus.

The boom F is made distensible, being composed of the slotted sections *m* and *m*², clamped together by the headed bolts *m*³ and clamping-nuts *m*⁴, so that by temporarily loosening the nuts the members *m* and *m*² may be slid endwise, one relatively to the other to lengthen or shorten the boom, so that the presentation of the shovel-buckets to the earth may be more or less distant from the center of the apparatus, as desired.

The boom F has its position with the downward inclination more or less, as shown in Fig. 1, by gravity and as far as permitted by the suspending-tackle, consisting of windlass *o*, tackle-blocks *o*² *o*³, secured on the upright frame B and on an outer portion of the boom, respectively, and the rope *o*⁴, one end

of which is connected to the ring-eye of the tackle-block o^3 , thence passing upwardly around block o^2 , returning around the tackle-block o^3 , and thence extended upwardly again to winding connection with the windlass, which, as usual, has a winding-crank o^5 , a ratchet o^6 , and a pawl o^7 . Of course the tackle-rope and tackle therefor may be arranged for the suspension and limiting purposes relatively to the boom F in a different manner from that specifically shown, if desired, for either greater or less purchase.

The boom G, pivoted at k to the platform C opposite the place of pivotal connection j for the boom F, has pivotally connected to it at p^3 the bar M, provided with the rack-teeth q , which engage with the pinion-wheel s in a train of gearing mounted on the upright framing B, said bar being borne upon at its upper edge by the roller r , which constrains the said bar M in its longitudinal movements to remain with its rack-teeth in engagement with the aforesaid pinion s . The train of gearing in which said pinion s is a part comprises the larger gear-wheel s^2 on the same arbor with the pinion s , which meshes into a pinion s^3 on the same arbor, with a larger gear-wheel s^4 , which meshes into a pinion s^5 , on the arbor of which is a crank-shaft s^6 . The train of gearing aforementioned is operative with slight speed and great power upon the bar M to cause its endwise motion, and as a consequence the swinging of the boom G to a different inclination to adapt the excavator to have the shovel-buckets thereof work through a different course, changing of the inclination of the boom G being usually accompanied by a changing of the inclination of the boom F and in some cases by a dis-tention of the latter boom.

The shovel-buckets J may advantageously be of the form shown in Fig. 3, comprising a scoop-shaped body, of which u is the edge of presentation to the earth, the opposite end being upwardly rounded, and this appliance has adjacent its end u the cross-tie member u^2 , provided with vertical ears u^3 , through which and the sides or cheeks u^4 of the bucket securing-rivets are passed, and the said tie member has the longitudinal extensions u^5 u^6 . The tie members are riveted at u^6 to the sprocket-chains, the said extensions u^5 having a suitable length of bearing on the chains to prevent undue tilting of the shovel-buckets relatively to the chain, especially during the time of taking earth.

The rounded end portion of the shovel-bucket has the reinforcing-pieces u^7 u^8 in the lines of the chains to prevent the latter from wearing the bucket near the rear corners thereof.

The harrowing device K, as shown in Fig. 4, comprises cross member v , of a length to extend across from one chain to the other, overlapping the chains, and the longitudinal

members v^2 v^3 , at the extremities of which and distanced from the cross member v such members v^2 are riveted to the chains, as indicated at v^3 , and a plurality of tines v^4 are secured to and extend angularly from the cross member v .

The apparatus having the parts thereof adjusted for excavation and the truck being moved to the proper place at which the work is to be done, the running of the engine insures a continuous traveling movement of the sprocket-chains, causing the shovel-buckets to have circuits through a path such as clearly understood on reference to Fig. 1 of the drawings, the harrowing devices when used moving in advance of the shovel-buckets to loosen the ground, so that under some conditions the buckets will be enabled to freely take the earth. The buckets becoming filled and carried upwardly around the guide-sheaves i automatically discharge the earth therefrom adjacent the outside of the sheaves i , the earth falling into a cart, if desired, or falling on the ground in a pile at a place remote from that of the excavation. From time to time the boom F may be lowered to give increased depression in the course of the shovel-buckets, which may be done by releasing the windlass-pawl and unwinding the windlass to permit of the down swinging under its weight of the boom, and the path of the buckets may be further modified by imparting endwise movement to the bar M either inwardly or downwardly. From time to time the truck may be moved so as to bring the carrier-chains for the shovel-buckets into a different plane of action, and for the work of digging trenches or ditches the platform C will be swung around transversely of the longitudinal line of the truck proper, so that the plane of progression of the bucket-chains is parallel with the longitudinal line of the truck, and then moving the truck forwardly as the work progresses the trench or ditch of indefinite length may be dug.

On desiring to transport the excavating device the boom F may by the tackle be swung upwardly clear of the ground more or less, as indicated by the dotted lines in Fig. 1, and the boom G may also be swung into an upright or approximately upright position for transportation.

Having thus described my invention, what I claim, and desire to secure by Letters Patent, is—

1. In an excavating apparatus, in combination, a support, duplicated booms, extended outwardly at opposite sides of said support, one pair downwardly inclined and the other pair upwardly inclined, and having wheels at their extremities, a pair of centrally-located elevated wheels, a pair of flexible carriers running around the sets of wheels, means for imparting traveling movements to the flexible carriers, and shovel-buckets secured to the flexible carriers.

2. In an excavating apparatus, in combination, a support, pairs of booms, extended outwardly at opposite sides of said support, carrying sprocket-wheels, one of said pair of booms being pivotally connected to said support and means for holding said paired booms in any desired inclination, centrally-located elevated sprocket-wheels, flexible carriers running around the sets of said sprocket-wheels, an engine on said support having driving connection with said elevated sprocket-wheels, and bucket-shovels carried by said flexible carriers.

3. In an excavating apparatus, in combination, a support, duplicated booms extended outwardly at opposite sides of said support, one pair downwardly inclined and the other pair upwardly inclined, and all thereof having wheels at their extremities, a pair of centrally-located elevated wheels, and a pair of wheels located below said support, a pair of flexible carriers running around the sets of wheels, means for imparting traveling movements to the flexible carriers, and shovel-buckets secured to the flexible carriers.

4. In an excavating apparatus, in combination, a support, booms F and G extending in pairs outwardly at opposite sides of the support, having wheels at their extremities, said booms being longitudinally distensible and having means for confining the members in their relative set positions, and centrally-located elevated wheels, flexible carriers running around the sets of wheels, and means for imparting traveling movements to the carriers, shovel-buckets secured on, and movable with, the carriers, also carried by said flexible carriers.

5. In an excavating apparatus, a portable support having an elevated frame thereon, the paired booms F pivotally connected to, and extended outwardly from, the side of said support, and having sprocket-wheels at their extremities, oppositely-extended booms G, and means for holding them in their desired line of projection, and guide-wheels at the extremities of said booms G, sprocket-wheels mounted on said elevated frame, and means for driving them, sprocket-chains running around the respective sets of guide-wheels, having shovel-buckets thereon, a windlass mounted on said frame, and a flexible connection secured to the paired booms F and having a winding engagement with the windlass.

6. In an excavating apparatus, a portable support having an elevated frame thereon, the paired booms F pivotally connected to, and extended outwardly from, the side of said support, and having guide-wheels at their extremities, oppositely-extended booms G, and means for holding them in their desired line of projection, and guide-wheels at the extremities of said booms G, sprocket-wheels mounted on said elevated frame and means for driving them, sprocket-chains running

around the respective sets of wheels, having shovel-buckets thereon, a windlass mounted on said frame, tackle-blocks on the frame and also connected to said paired booms and a flexible connection, secured to the boom tackle-block; and having a running engagement around both said tackle-blocks, and a winding engagement with the windlass.

7. In an excavating apparatus, a portable support having an elevated frame thereon, the paired booms F connected to, and extended outwardly and downwardly from, one side of said support, having guide-wheels at their extremities, the paired booms G extended oppositely from the booms F, and in an upward inclination, having guide-wheels at their extremities, a pair of sprocket-wheels having an elevated location on said frame, and means for driving them, carrier-chains running around the respective sets of said wheels having shovel-buckets mounted thereon, a bar M having a connection with said paired booms G, and means for imparting longitudinal movements to said bar, for the purposes set forth.

8. In an excavating apparatus, a portable support having an elevated frame thereon, the paired booms F connected to, and extended outwardly and downwardly from one side of said support, having guide-wheels at their extremities, the paired booms G extended oppositely from the booms F, and in an upward inclination, having guide-wheels at their extremities, a pair of sprocket-wheels having an elevated location on said frame, and means for driving them, carrier-chains running around the respective sets of said wheels having shovel-buckets mounted thereon, a rack-toothed bar M having a pivotal connection with said paired booms G, a gear-wheel on said frame with which the teeth of said bar engage, and means for turning said gear-wheel.

9. In an excavating apparatus, in combination, a portable support having an elevated frame thereon, the oppositely-extending paired and pivotally-connected booms F and G carrying pairs of guide-wheels, the pair of sprocket-wheels on the elevated frame, an engine and driving connections between it and said latter sprocket-wheels, the shovel-bucket-carrying chains arranged to run around the two side sets of said wheels, means for supporting the boom F in its proper inclination, the bar M pivotally connected to the paired booms G and having the rack-teeth *q*, a gear-wheel *s* with which said rack-teeth engage, the roller *r* having a bearing on the side of the said bar opposite from the rack-teeth, and a train of speed-reducing gearing in connection with the gear-wheel *s*, and means for moving same, substantially as described.

10. In an excavating apparatus, in combination, a vehicle having a rotationally-shiftable platform, with an elevated frame thereon, the oppositely-extending paired and pivotally-

connected booms F and G carrying pairs of guide-wheels, and the pivoted booms L depending below said support having the pair of guide-wheels, an engine, and driving connections between it and said latter guide-wheels, the shovel - bucket - carrying chains arranged to run around the two side sets of said wheels, a windlass-connected tackle for supporting the boom F in its proper downward inclination, the bar M pivotally connected to the paired booms G and having the rack-teeth q, a gear-wheel s with which said rack-teeth engage, the roller r having a bearing on the side of the said bar opposite from the rack-teeth, a train of speed-reducing gearing in connection with the gear-wheel s, and means for moving same, substantially as described.

11. In an excavating apparatus, a vehicle having a horizontal platform and an engine mounted thereon provided with a sprocket-wheel f on its driving-shaft, and the elevated frame having the shaft d with paired sprocket-wheels b b and sprocket-wheel g², the oppositely-extended booms F and G in pairs respectively downwardly and upwardly inclined, having pairs of chain-wheels thereon, and means for sustaining said booms in their given set inclined positions, a sprocket-chain running around the sprocket-wheels f and g², and the pair of sprocket-chains D, in engagement with the sprocket-wheels b b and the boom-carried chain-wheels, and shovel-buckets mounted on the pair of sprocket-chains D D, substantially as described.

12. In an excavating apparatus, a supporting structure comprising a frame and extension-booms in pairs with chain-wheels and a pair of carrier-chains running therearound, means for imparting a traveling motion to the carrier-chains, and shovel-buckets of scoop shape, comprising a bottom with an upturned end portion, sides, and an open front, and a cross member u², connecting the sides near the front end, in a plane above the bottom, said cross member having riveted connection with the chains.

13. In an excavating apparatus, a support-

ing structure comprising a frame and extension-booms in pairs with chain-wheels and a pair of carrier-chains running therearound, means for imparting a traveling motion to the carrier-chains, and shovel-buckets of scoop shape, comprising a bottom with an upturned end portion, sides, and an open front, and a cross member u², connecting the sides near the front end, in a plane above the bottom, said cross member having riveted connections with the chains, and having the longitudinal extensions u⁵ along the lines of the chains and having said bucket, having at its opposite upturned end the reinforcing - blocks adjacent the courses of the chains.

14. In an excavating apparatus, a supporting structure comprising a frame and extension-booms in pairs, with chain-wheels and a pair of carrier-chains running around respective sets of the wheels, means for imparting traveling motion to the carrier-chains, shovel-buckets, mounted on the chains, and the harrowing device consisting of longitudinal members v³ v² connected to the chains, and the cross member v, connecting the longitudinal members and having the angularly-projected tines v⁴, substantially as described. 65

15. In an excavating apparatus, a supporting structure comprising a frame and extension-booms in pairs, with chain-wheels, and a pair of carrier-chains running around respective sets of the wheels, means for imparting traveling motion to the carrier-chains, shovel-buckets, mounted on the chains, and the harrowing device consisting of longitudinal members v³ v², and the cross member v, connecting the longitudinal members having the angularly-projected tines v⁴, said longitudinal members v² having connections with the chains at the end portions farther from the said tine-carrying cross member. 70 75 80
